UNITED STATES PATENT OFFICE

HARRY B. HULL, OF DAYTON, OHIO, ASSIGNOR TO FRIGIDAIRE CORPORATION, OF DAYTON, OHIO, A CORPORATION OF DELAWARE

REFRIGERATING APPARATUS

Application filed April 25, 1930. Serial No. 447,364.

This invention relates to refrigerating apparatus and more particularly to a mechanical refrigerating apparatus provided with means for insulating objectionable noises produced by said apparatus.

This application is a continuation in part of my copending application for refrigerating apparatus Serial No. 292,665, filed July 14, 1928.

10 An object of this invention is to provide a sound insulating enclosure for a mechanical refrigerant liquefying unit, which enclosure permits the circulation of air through said enclosure and at the same time muffles any 15 sound produced within the enclosure.

Another object of this invention is to arrange the sound insulating enclosure in such a manner so as to permit ready access to the refrigerant liquefying unit.

20 Another object is to provide a mechanical refrigerator cabinet of symmetrical proportions which utilizes one of the unexposed sides for ventilation and a partition of the building in which it is located as an aid in 25 dampening the noise of the machinery.

Further objects and advantages of the present invention will be apparent from the following description, reference being had to the accompanying drawings, wherein a preferred form of the present invention is clearly 30 shown.

In the drawings:

Fig. 1 is a top view in cross section of a cabinet embodying features of my invention;

35 Fig. 2 is a vertical view in cross section taken along the line 2—2 of Fig. 1; and

Fig. 3 is a vertical view in cross section taken on the line 3—3 of Fig. 1.

40 In practicing this invention I provide a cabinet of symmetrical proportions, preferably having rectangular outer dimensions in which the food or cooling compartment is placed in the upper portion of the cabinet for ready accessibility and the machinery compartment is placed below, and in which the walls of the cabinet together with a partition of the building in which it is placed permits the ventilation and cooling of the machinery

45 but prevents the passage of noises of the ma-

chine into the room in which the cabinet is placed.

Referring to the drawings the numeral 20 designates in general a refrigerating apparatus embodying features of my invention and which includes refrigerator cabinet 21 provided with a generally rectangularly cross-sectioned cooling compartment 22 and a sound dampening enclosure or generally rectangularly cross-sectioned machine compartment 23. The outer contours of horizontal cross-sections of these compartments are preferably substantially equal. The refrigerating apparatus comprises a mechanical refrigerant liquefying unit designated 25. 55 The unit 25 includes a refrigerant circulating element comprising certain parts which in general are moving or sound producing such as an electric motor 27 and a compressor 28. The motor is adapted to drive the compressor by means of belt 29. The compressor is adapted to deliver compressed refrigerant through pipe 31 to an air cooled condenser 32 where the refrigerant is liquefied and from which it is delivered through pipe 35 60 to a receiver 37. From the receiver the refrigerant is delivered through pipe 39 to a cooling unit 40 disposed within the cooling compartment 22. The refrigerant after being evaporated is returned to the compressor 28 through pipe 42. As shown, the compressor and motor are mounted on a resilient platform 44 which permits vibrations without transmitting them to the cabinet. 65

A unit of the type hereinbefore described is liable to produce objectionable noises and for this reason I have provided the sound insulating enclosure for the moving or sound producing parts of said unit. This enclosure comprises suitable sound deadening walls 50 70 and 51. The compartment 23 is provided with an opening 54, which may be equal to substantially the entire vertical cross-sectional extent of the compartment 23, for the circulation of air into and out of the compartment 23. The cabinet 20 is placed adjacent a wall or partition 57 of the room or building in which the refrigerator is placed in such a manner so as to leave a clear opening to the atmosphere. The cabinet also includes a 75

hinged or otherwise ready removable door or closure member 60 for access to the machinery. If desired, the pipes 39 and 42 leading from the unit 25 to the cooling unit 40 may be of sufficient length so as to permit the removal of the unit 25 from the compartment 23 through the opening closed by door or closure member 60 without disconnecting said pipes. All of the walls of the compartment 23, including the door or closure member 60, may be provided with noise absorbing material of the character hereinafter described.

The construction is such that the noises produced by the machinery are absorbed by the walls. Thus no noises are reflected from the walls and consequently only the noises coming directly from the machinery can pass through the opening 54. No noises are reflected through the opening. Under some conditions the passage of these direct or unreflected noises through the air opening are practically insufficient to render the operation of a machine audible when the air passage is left entirely open. One of the conditions when this is done is when the air passage is placed in the rear of the machinery compartment of the cabinet and the compartment is placed near a wall of the room in which the compartment is located as hereinbefore described.

The sound insulating walls 50, 51 and the sound insulating door or closure member 60 is made of any suitable material presenting a surface or body adapted to absorb, dampen or prevent the passage of noises. As a specific embodiment, the sound deadening material is a fluffy comminuted or other material presenting a surface or body adapted to absorb, dampen and prevent the passage of noise. This material may be applied in any manner. It may be compressed or compacted, and confined to any suitable degree either before or during application. It may be compressed into a sheet, packet or board like form and may be applied around the moving parts of the machinery in any desired manner. In this particular embodiment, as shown on walls 50 and 51, the noise deadening material comprises substantially a flat packet made by forming a packet having an exposed face of meshed wire. This packet is substantially slab like. These packets are made in sizes adapted to cover the walls 50 and 51. Within the packet formed by the meshed wire is placed the desired noise dampening material. A convenient construction comprises a wire packet within which is placed any desired fluffy or comminuted material, such as balsam wool, wood shavings, wood pulp or in fact any desired material. The packets thus formed are secured to the metal sides of the cabinet in any desired manner.

The sound insulating material on the door or closure member 60 is made of any suitable

material presenting a surface or body adapted to absorb, dampen or prevent the passage of noises. It is compressed into a sheet or board like form, and in the particular embodiment the material is exploded wood pulp compressed sufficiently to be self-sustaining in a board like form. In order to prevent fibers from flying through the mechanism, this board is coated with aluminum base paint. The sound deadening material may be insertable along the interior of the metal casing of the door or closure member.

By coating the sound insulating material with aluminum paint, a surface is presented which prevents the lint from flying off the sound insulating material. Any means adapted to prevent the lint from flying without impairing the sound deadening character of the surface may be substituted. The surface presented to the sound is of a sound rebound checking character. Obviously the sound deadening material used on walls 50 and 51 may be used on door or closure member 60, likewise the sound deadening material used on door or closure member 60 may be used on walls 50 and 51.

In the operation of the device, air freely enters the compartment 23 and circulates therein in the direction of the arrows shown in Fig. 1. Thus the air circulates around the compressor and motor and is discharged by the fan 75 carried by the armature shaft of the motor 27. The air discharged by the fan 75 passes along the finned portions of the condenser 32 to cool the condenser, whence the air passes on out into the atmosphere. It has been found that a distance of from one and one-half inches to five inches between the wall 57 and the cabinet 21 is a very satisfactory distance. Because of the sound-insulating character of the walls 50, 51, door or closure member 60 and partition 57, sounds produced in the enclosure are prevented from passing out into the surrounding atmosphere. For this reason a very silent mechanical refrigerating apparatus is produced.

This invention is also a continuation in part of my copending application for refrigerating apparatus, Serial No. 302,043, filed August 25, 1928.

While the form of embodiment of the invention as herein disclosed, constitutes a preferred form, it is to be understood that other forms might be adopted, all coming within the scope of the claims which follow.

What is claimed is as follows:

1. A noiseless unitary refrigerator comprising a food compartment and a machinery compartment, said machinery compartment including a plurality of sound dampening walls, a refrigerating system in said refrigerator comprising an evaporator in said food compartment, a refrigerant circulating element connected to said evaporator and located in said machinery compartment, said

- circulating element including a compressor and a motor for driving said compressor, one of said walls having an opening for said machinery compartment for the circulation of air into and out of said machinery compartment, said opening being located in a wall of said machinery compartment to be placed adjacent a partition of the building in which the refrigerator is to be installed, and an imperforate sound dampening closure member on another wall of said machinery compartment for access to said refrigerant circulating element.
2. A noiseless unitary refrigerator comprising a food compartment and a machinery compartment, said machinery compartment including a plurality of sound dampening walls, a refrigerating system in said refrigerator comprising an evaporator in said food compartment, a refrigerant circulating element connected to said evaporator and located in said machinery compartment, said circulating element including a compressor and a motor for driving said compressor, one of said walls having an opening for said machinery compartment for the circulation of air into and out of said machinery compartment, said opening being located in a wall of said machinery compartment to be placed adjacent a partition of the building in which the refrigerator is to be installed, means for circulating air into and out of said machinery compartment through said opening, and a sound dampening closure member on another wall of said machinery compartment for access to said refrigerant circulating element.
3. A noiseless unitary refrigerator comprising a food compartment and a machinery compartment, said compartments being of substantially the same horizontal outside dimension with said machinery compartment being disposed below said food compartment, said machinery compartment including a plurality of sound dampening walls, a refrigerating system in said refrigerator comprising an evaporator in said food compartment, a refrigerant circulating element connected to said evaporator and located in said machinery compartment, said circulating element including a compressor and a motor for driving said compressor, one of said walls having an opening for said machinery compartment for the circulation of air into and out of said machinery compartment, said opening being located in a wall of said machinery compartment to be placed adjacent a partition of the building in which the refrigerator is to be installed, means for circulating air into and out of said machinery compartment through said opening, and a sound dampening closure member on another wall of said machinery compartment for access to said refrigerant circulating element.
4. A noiseless unitary refrigerator comprising a food compartment and a machinery compartment, said machinery compartment including a plurality of sound dampening walls, a refrigerating system in said refrigerator comprising an evaporator in said food compartment, a refrigerant circulating element including a compressor and a motor for driving said compressor, one of said walls having an opening for said machinery compartment for the circulation of air into and out of said machinery compartment, said opening being located in a wall of said machinery compartment to be placed adjacent a partition of the building in which the refrigerator is to be installed, and an imperforate sound dampening closure member on a wall away from the rear of said machinery compartment for access to said circulating element.
5. A noiseless unitary refrigerator having a machinery compartment, said machinery compartment including a plurality of sound dampening walls, a refrigerant circulating element in said machinery compartment, said refrigerant circulating element including a compressor and a motor for driving said compressor, one of said walls having an opening for said machinery compartment for the circulation of air into and out of said machinery compartment, said opening being located in a wall of said machinery compartment to be placed adjacent a partition of the building in which the refrigerator is to be installed, means for circulating air into and out of said machinery compartment through said opening, and a sound dampening closure member on another wall of said machinery compartment for access to said refrigerant circulating element.
6. A noiseless unitary refrigerator comprising a machinery compartment, said machinery compartment including a plurality of sound dampening walls, a refrigerant circulating element in said machinery compartment, said refrigerant circulating element including a compressor and a motor for driving said compressor, a rear wall having an opening for said machinery compartment for the circulation of air into and out of said machinery compartment, said rear wall of said machinery compartment to be placed adjacent a partition of the building in which the refrigerator is to be installed, and an imperforate sound dampening closure member on a wall away from the rear of said machinery compartment for access to said circulating element.
7. A noiseless unitary refrigerator comprising a food compartment and a machinery compartment, said machinery compartment including a plurality of sound dampening walls, a refrigerating system in said refrigerator comprising an evaporator in said

food compartment, a refrigerant liquefying unit connected to said evaporator and located in said machinery compartment, said liquefying unit including a motor driven compressor, an air cooled condenser and a fan for circulating air into and out of said machinery compartment, a rear wall having an opening in said machinery compartment for the circulation of air into and out thereof by said fan, 5 said rear wall of said machinery compartment to be placed adjacent a partition of the building in which the refrigerator is to be installed, and a sound dampening closure member on a wall away from the rear of said 10 machinery compartment for access to said liquefying unit.
